UNITED STATES PATENT OFFICE

164,169

HOUSING FOR DISPENSING APPARATUS

Walter M. Harks, Fort Wayne, Ind.

Application March 22, 1951, Serial No. 14,583

Term of patent 14 years

(Cl. D52—2)

To all whom it may concern:

Be it known that I, Walter M. Harks, a citizen of the United States, residing in the city of Fort Wayne, county of Allen, State of Indiana, have invented a new, original, and ornamental Design for Housing for Dispensing Apparatus, of which the following is a specification, reference being had to the accompanying drawing, forming a part thereof.

The sides opposite the elevations of Figures 1 and 3 are of substantially the same appearance as said elevations respectively.

I claim:

The ornamental design for a housing for dispensing apparatus, as shown and described.

WALTER M. HARKS.
